UNITED STATES PATENT OFFICE.

EDWARD ERMOLD, OF NEW YORK, N. Y.

BOTTLE-LABELING MACHINE.

No. 923,501.

Specification of Letters Patent.

Patented June 1, 1909.

Application filed July 23, 1908. Serial No. 444,885.

To all whom it may concern:

Be it known that I, EDWARD ERMOLD, a citizen of the United States of America, residing at New York, in the borough of Manhattan, county and State of New York, have invented certain new and useful Improvements in Bottle-Labeling Machines, of which the following is a specification.

This invention relates to an improved machine for labeling bottles of that class in which two labels, a body-label and a neck-label, are applied by one operation to the body and neck of the bottle; and for this purpose the invention consists of a bottle-labeling machine which comprises a stationary bottle-rest, label-receptacles located above the bottle at the upper part of the machine, paste-supply rollers at each side of the machine, pickers which take up a paste-supply from the paste-rollers during their upward motion, means for tilting the pickers into vertical position during their upward movement for taking up the paste from the paste-rollers, means for moving the pickers into horizontal position below the label-receptacles so as to take up the lowermost labels in the same, means for returning the pickers for delivering the labels to the body and neck of the bottle, a fulcrumed presser-arm having presser-blocks for the body and neck labels, and pairs of oscillating wipers, one pair for the body-label and the other pair for the neck-label, for applying the labels to the bottle in connection with the presser-blocks of the fulcrumed presser-arm.

The invention consists further of certain details of construction, such as means for imparting the proper turning motion to the pickers during their ascending movement, means for actuating the wipers for the body and neck labels, and other details which will be fully described hereinafter and finally pointed out in the claims.

In the accompanying drawings, Figure 1 represents a front-elevation of my improved bottle-labeling machine, Fig. 2 is a side-elevation of the same, Fig. 3 is a sectional front-elevation of the upper part of the machine, showing the operative parts on a larger scale, Fig. 4 is a side-elevation of the upper part of the machine, partly in section and drawn on a still larger scale, showing the machine from the side opposite that shown in Fig. 2, Fig. 5 is a horizontal section on line 5-5, Fig. 3, showing a plan-view of the presser-arm, pickers and paste-supply rollers

and their operating mechanism, Fig. 6 is a detail sectional front-view of the picker-operating mechanism, Fig. 7 is a detail front-elevation, drawn on a larger scale, of a pair of wipers for applying a looped neck-label to the neck of a bottle, and the operating mechanism of the same, Figs. 8, 9 and 10 are respectively a front-elevation, a side-elevation, and a rear-elevation of one of the wipers for applying a looped neck-label, Fig. 11 is a detail plan-view, partly in section, of the receptacles for the body and neck labels, Fig. 12 is a horizontal section on line 12-12, Fig. 1, drawn on a larger scale, Fig. 13 is a detail side-elevation of the motion-transmitting mechanism for the wipers for the body-labels, and Fig. 14 is a detail front-elevation of the wipers for the body-labels and the actuating mechanism of the same.

Similar letters of reference indicate corresponding parts throughout the several figures.

My improved bottle-labeling machine makes use of the usual instrumentalities in bottle-labeling machines, but adapts the same to the double function of applying simultaneously a body-label and a neck-label to the bottle.

The machine consists of a stationary bottle-rest the shape of which corresponds to the shape of the bottles to be labeled, receptacles for the body and neck labels which are located vertically above the bottle-rest, pairs of paste-supply rollers, one at each side of the machine approximately midway between the bottle and the label-receptacles, two pairs of vertically reciprocating pickers which are tilted during their upward motion so as to take up the paste-supply from the paste-rollers and moved in horizontal position below the label-receptacles for taking up the labels from the same, an oscillating presser-arm provided with presser-blocks for holding the labels on the body and neck of the bottle, two pairs of wipers, one for the body-label and the other for the neck-label, and mechanism for transmitting the different motions from a cam-shaft to the operating parts.

The supporting frame.—All the operative parts of the improved bottle-labeling machine are supported on a frame F, which consists of a four-legged base f, at one side of which is arranged a foot-treadle t for starting the machine and at the other side of which is arranged the clutch-operating

hand-lever t^1 by which the power is applied to the driving shaft S . By placing the movable clutch-member in mesh with the clutch-member on the driving-pulley, power is transmitted to the driving-shaft S , while by operating the foot-treadle a clutch mechanism is actuated, by which the cam-shaft S^1 is thrown into gear with the driving-shaft S , and thereby the machine started. The cam-shaft is provided with a fly-wheel, and adjacent to the same with a brake-wheel that is operated in connection with a spring-actuated brake-shoe so as to impart a uniform motion to the cam-shaft. Above the base f is supported the upright portion f^1 of the frame F on which the operating mechanisms of the different operative parts of the machine are supported.

The bottle-rest.—About midway of the height of the supporting frame is located the stationary bottle-rest B . The bottle-rest is made of concave shape and adapted to the shape of the bottle to be labeled. It is capable of adjustment in upward and downward direction according to the various sizes of the bottles to be labeled. The bottle-rest is provided at its rear-end with a stop b , which is capable of adjustment in forward or backward direction by means of a clamping screw and nut. At the front-end of the bottle-rest is a downwardly curved lip for facilitating the placing in position and removing of the bottles. After the bottle-rest and bottle-stop are once adjusted to the proper size and shape of the bottles to be labeled, they remain stationary throughout the labeling operation.

The paste-supply mechanism.—On both sides of the machine and symmetrically to the vertical center-plane of the same, are arranged two sets of paste-supplying mechanisms D , which are made of any approved construction, and which consist of paste-receptacles d^1 that are supported on horizontal bracket-plates d^2 of the supporting frame F and provided each with a pair of take-up rollers d^3 and paste-supply rollers d^4 . In each paste-receptacle d^1 there is one take-up roller d^3 for the body-labels and a smaller take-up roller d^3 for the neck-labels, these rollers being located on the same shaft; and the paste-supply rollers d^4 likewise consist of a large roller for the body-labels, adjacent the large roller d^3 , and a small roller on the same shaft, adjacent the small take-up roller d^3 . Rotary motion is imparted to the shafts of the paste-supply rollers d^4 by two sets of gear-wheels d^5, d^6 and two sets of bevel gear-wheels d^7, d^8 from a transverse shaft d^9 located at the rear-part of the machine, which shaft is provided with a sprocket-wheel d^9 that is engaged by an endless sprocket-chain d^{10} to which motion is imparted from a sprocket-wheel d^{11} on the driving-shaft S , as shown clearly in Fig. 1. Each pair of

paste-supply rollers d^4 is rotated in intermittent contact with its pair of take-up rollers d^3 , which are placed on shafts parallel with the shafts of the paste-supply rollers, the latter receiving rotary motion from the sprocket-wheel shaft d^7 and the intermediate gear-wheel transmissions for taking up the paste from the take-up rollers as soon as they are placed in contact with the same, as shown clearly in Fig. 5 and in dotted lines in Fig. 3. The shafts of the take-up rollers are supported in suitable bearings of the paste-receptacles. Blades d^{12} are held in contact with the take-up rollers by a weight or other suitable tension device d^{13} applied to the shafts of the blades, said shafts turning in bearings at the rear-parts of the paste-receptacles, said blades regulating the supply of paste to the take-up and supply rollers. The supporting brackets d^2 of the paste-receptacles d^1 are supported on upright side-arms f^2 , which arms are attached at their upper and lower ends to the upright main-standard f^1 of the frame F . The shafts of the paste-supply rollers d^4 are supported in bearings of pivot-links d^{14} which are applied at their lower ends to pivot-rods d^{15} that are supported in eyes at the front and rear parts of the bracket-plates, so that the paste-supply rollers can be moved sidewise into contact with the take-up rollers to receive the paste from the same, and inwardly to deliver the paste taken up by them to the pickers. This lateral motion is imparted to the paste-supply rollers by oscillating cam-levers d , which are pivoted at their upper ends to the frame F , and which are operated by anti-friction rollers d^{16} (Fig. 5) of the picker-operating mechanism. The lower ends of the levers d^{15} are yieldingly connected by a helical spring d^{17} which holds the cam-shaped faces of the levers in contact with the antifriction rollers d^{16} . The oscillating levers d are connected with the shafts of the pivot-links d^{14} by pins d^{18} located about midway of the levers d .

The pickers and picker-motion.—The pickers are shown in Figs. 1, 3 and 5. Two pairs of pickers p and p^1 are used, one pair for transmitting the body-label from the body-label receptacle to the body of the bottle and the other pair for transmitting the neck-label from the neck-label receptacle to the neck of the bottle. The pickers for the body-label and the neck-label are placed on picker-arms p^2 , one at each side of the vertical center-plane of the machine, which picker-arms are applied at their rear-ends to oscillating sleeves p^3 that are placed on parallel horizontal supporting rods p^4 which are attached to a crosshead p^5 that is attached to a guide-rod p^6 which slides in two bearings p^7 at the upper and middle parts of the supporting frame F , said crosshead receiving vertically reciprocating motion from a crank-arm p^8 on the

cam-shaft S^1 and an intermediate slotted oscillating lever p^{10} which is pivoted at the front-end to a bracket-arm f^8 of the supporting frame F and at the rear-end to an oscillating link p^{11} having a socket p^{12} to which is attached by means of jam-nuts p^{13} a vertical rod p^{14} which carries at its upper end the sleeve p^{15} of a second link p^{16} that is pivoted to the crosshead p^5 , said link being cushioned by a helical spring p^{17} placed around the upright rod p^{15} and held at its lower end by a nut p^{18} and jam-nut p^{19} on the lower part of said rod. The rotation of the cam-shaft S^1 imparts oscillating motion to the slotted lever and thereby a vertically reciprocating motion to the crosshead p^5 , the lower and upper positions of the pickers and of the oscillating lever actuating the same being shown respectively in dotted and full lines in Fig. 4. 20 The cushioning spring p^{17} serves to give a certain elasticity to the pickers and their operating parts when taking up the labels at the lower parts of the label-receptacles.

At the rear-ends of the sleeves p^3 are arranged spring-actuated knuckles e , the helical springs e^x of which are connected to short uprights e^4 on the crosshead p^5 , as shown in Fig. 6. The knuckles e are provided with outwardly projecting toes e^2 and opposite the same with rollers e^3 which move along the sides of a stationary guide-plate e^4 during the upward motion of the picker-arms after they have been turned on their axis into vertical position, as shown in dotted lines in Fig. 3. 35 During the upward motion of the pickers, the toes e^2 of the same are placed in contact with rollers e^6 at the inner ends of short fulcrumed and spring-actuated levers e^7 and thereby turned into vertical position, so that the rollers e^3 engage the sides of the stationary guide-plate e^4 and that the pickers receive during their upward motion the supply of paste from the paste-rollers d^4 . As soon as the rollers e^3 clear the upper edges of the stationary guide-plate e^4 , the oscillating sleeves of the picker-arms are released and turned into a horizontal position below the label-receptacles. During the downward motion of the pickers, the toes e^2 of the same pass over the rollers e^6 of the short levers e^7 which "give" sufficiently to permit the passage of the picker-sleeves.

The ends of the crosshead p^5 are curved in forward direction and provided with face-plates g which slide on the rear-faces of the stationary upright guide-rails g^1 so as to have an absolutely steady reciprocating motion and permit the proper movement of the pickers, namely, the turning of the same during their upward motion into vertical position so as to take up the paste from the paste-rollers and the tilting of the same into horizontal position below the lower ends of the label-receptacles, while during the descending motion of the pickers they remain in horizontal

position so as to bring the labels taken up from the label-receptacles over the neck and body of the bottle.

The label-receptacles.—The label-receptacles are shown in Figs. 1, 2, 3, 4 and 11. They are supported on horizontal rods h and composed of a number of upright fingers h^1 that are supported in pairs on cross-bars h^2 , which are placed on the rods h and on parallel arms h^3 that are attached to the cross-bars h^2 . 75 The finger-supporting cross-bars are made adjustable on the horizontal rods h and the parallel arms h^3 on the cross-bars, so as to provide for different sizes of labels within certain limits. The lower ends of the upright fingers are provided with inwardly tapering lips on which the pile of labels which is placed in each receptacle is supported. The fingers permit the free entry of the pickers when they arrive in their position below the label-receptacles so as to form contact with and take up the lowermost labels and remove the same by the downward motion of the pickers from the piles of labels. The piles of labels in the receptacles are pressed 80 in downward direction by the curved ends of a horizontal presser-bar h^4 which is pivoted to the lower end of a vertical center-bar h^5 and extended in forward and backward direction over the labels in both receptacles. 85 The center-bar h^5 is provided with a rack h^6 at one side and guided vertically in ways of a horizontal bracket-arm h^7 , which is capable of adjustment in forward and backward direction by a supporting sleeve h^8 and set-screw h^9 . The presser-bar h^4 , together with the label-receptacles, can be lifted by means of a crank-arm h^{10} so as to interrupt the label-feed. The shaft of the crank-arm h^{10} turns in suitable bearings on the supporting 90 mechanism of the label-receptacles, and is provided with a crank h^{11} which is connected by a pivot-link h^{12} with the supporting frame F . To the front-end of the horizontal bracket-arm h^7 is pivoted a weighted pawl h^{13} , the lower tapering end of which engages the teeth of the rack-bar h^5 and permits the horizontal presser-bar to slide with the rack-bar in downward direction as the piles of labels in the receptacles are gradually diminished in height. The presser-bar exerts 95 a downward center-pressure on the piles of labels, so that the lower labels form a slight bulge and facilitate thereby the contact with the paste-covered faces of the pickers as the same are moved upwardly into contact with the lowermost labels. By lifting the weighted pawl h^{13} , the presser-bar can be moved in its uppermost position above the label-receptacles so as to permit the refilling of the same. 100

The oscillating presser-arm.—At the center-part of the supporting frame is supported a fulcrumed presser-arm i , which when in its position of rest is in an upright position, and which serves when being swung in downward 105 110 115 120 125 130

direction for pressing on the body and neck-labels as they are delivered by the descending motion of the pickers onto the body and neck of the bottle, so as to be held thereon for the action of the wipers. The oscillating presser-arm i is fulcrumed at its lower end to the supporting frame and pivoted below its fulcrum by a short arm i^1 to the upper end of a link i^2 , the lower end of which is provided with a sleeve i^3 and connected by a rod i^4 having a cushioning spring i^5 with the sleeve i^6 of a lower link i^6 which is applied to the forward-end of an oscillating lever i^7 that is pivoted to the supporting frame F , as shown in Fig. 4. The connecting rod i^4 between the upper and lower links of the oscillating presser-arm i is provided at its upper end with a head and at its lower end with a screw-nut and jam-nut that are attached at opposite sides of the sleeve of the lower link. The cushioning spring is interposed between the sleeve of the upper link and the jam-nut of the lower link so as to permit the yielding of the upper link when the oscillating presser-arm i forms contact with the bottle so as to prevent sudden blows or shocks that may exert an injurious influence on the bottle and labels placed thereon. The oscillating presser-arm i is operated by an antifriction roller i^8 on the oscillating lever i^7 and an actuating cam i^9 on the cam-shaft S^1 , the cam being so shaped as to produce at the proper time the required motion of the presser-arm. The presser-arm is provided with two presser-blocks i^{10} , i^{11} , a larger one for the body-label and a smaller one for the neck-label. The presser-block i^{10} for the body-label is guided by a pin i^{12} in a recess of the presser-arm and cushioned by a helical spring i^{13} that is inserted in a socket i^{14} at the rear-part of the presser-arm. The presser-block i^{11} for the neck-label is connected by a curved arm i^{15} with the upper end of the oscillating presser-arm and attached thereto by a fastening screw. The presser-block for the neck-label corresponds in size with the neck-label, and is made of inverted V-shape so as to hold the neck-label with its lower edges on the neck of the bottle, as shown in Fig. 3. The oscillating presser-arm is shown in upright or normal position of rest in full lines in Fig. 4 and in position on the body and neck of the bottle in Figs. 1, 2 and 3.

The wipers for the body-labels.—Two pairs of wipers are required, one pair w for applying the body-label to the body of the bottle and a second pair of wipers w^1 for applying the neck-label around the neck of the bottle. The wipers for the body-labels are constructed in the well known manner of yielding rubber plates that are supported in suitable holders at the upper ends of fulcrumed levers w^2 , the lower ends of which are fulcrumed at w^3 to a vertically guided sleeve w^3 which receives a vertically reciprocating

motion on an upright guide-rod w^4 at the top of which is a stop w^5 . This motion is produced by an oscillating lever w^6 which is fulcrumed at its rear-end to the frame F and actuated by a cam w^6 , the cam-groove of which engages an antifriction roller w^7 attached to the middle part of the oscillating lever w^6 .

The supporting levers for the body-wipers are connected by helical springs w^8 with a pair of oscillating levers w^9 , which are fulcrumed to lugs w^9 on the vertically reciprocating sleeve w^3 , concentrically with the wiper-supporting levers w^2 , and which serve for moving the wipers in outward direction. The oscillating motion is imparted to the wiper-moving levers w^9 , and to the wiper-supporting levers w^2 , by a cam w^{10} , the cam-groove of which operates an oscillating lever w^{11} which is fulcrumed at its rear-end to the frame F . The opposite end of the lever w^{11} is connected by a pivot-link w^{12} with one of the wiper-moving levers from which the motion is imparted to the second wiper-moving lever by a pin w^{13} at the end of the first lever w^{11} engaging a slot w^{14} at the end of the second lever, as shown in Figs. 13 and 14. By this mechanism the wipers w are spread apart during their upward motion so as to clear the bottle. At the beginning of the downward motion, the wipers are moved inwardly over the ends of the label which is held in proper position on the bottle by the presser-arm i , after which the downward motion of the wipers takes place so that the gummed under-side of the label is placed in adhesive contact with the bottle.

The neck-label wipers.—The wipers w^1 for the neck-labels can be made of the same construction as the wipers for the body-labels when an ordinary short label is placed transversely on the neck of the bottle. In many cases, however, the neck-label is so long that it goes all around the neck of the bottle, sometimes overlapping at the ends. A special construction for applying such labels is necessary. This special construction of the wipers and their operating mechanism is shown in Figs. 7, 8, 9 and 10, and consists of a pair of elbow-shaped knuckles v and thin spring-plates v^1 which are cut into small strips at about two-thirds of their length, before being bent at their ends. The acting wiper-ends consist of a number of bent-up elastic wiper-strips v^2 capable to adapt themselves to the various shapes of the bottle-necks. These elastic wiper-strips are attached to the elbow-shaped knuckles which are pivoted to short shanks v^3 at the upper ends of fulcrumed neck-wiper levers v^4 , which shanks are supported in sleeves of the neck-wiper levers. The upper ends of the elbow-shaped knuckles are provided with rollers v^5 that move over the neck of the bottle, guiding the elastic wiper-ends over the label

around the bottle-neck, while the upper ends of the fulcrumed wiper-levers move in downward and inward direction.

The whole neck-wiper device is suspended from pins v^6 which are attached to the upper ends of the body-wiper supporting levers so that the neck-wipers make the same combined motion as the body-wipers. To this motion is added a third one by means of a stationary cam-plate v^7 which acts on yielding rollers v^8 at the lower ends of the neck-wiper levers, so that their upper ends are forced to make an inward motion during their descending motion and produce the wiping action on the neck-label by guiding the neck-wipers by their rollers around the bottle-neck. The suspension of the neck-wiper levers from the body-wiper levers is effected by means of suspending rods v^{13} and v^{14} which are clamped to the pins v^6 by means of split sleeves v^{15} , as shown in Fig. 7, and extend downward from said pins, carrying at their lower ends laterally extending brackets v^{16} to the inner ends of which the neck-wiper levers v^4 are pivoted intermediately of their length by means of pivot-pins v^{17} . It will be noted that one of the neck-wiper levers is located higher than the other, as shown in Fig. 7, and the suspending rod v^{14} for the higher one is shorter than the suspending rod v^{13} of the other lever. Springs v^9 are arranged between the upper ends of the neck-wiper levers and the suspending brackets v^{16} for the same, and serve to hold the yielding rollers v^8 at the lower ends of the neck-wiper levers in contact with the cam-plate. The springs v^{10} interposed between the wiper-knuckles and the wiper-levers serve to bring the wiper-knuckles back into the former position after the wiping operation is finished, while springs v^{11} between the lower ends of the neck-wiper levers and pins on the shanks of the yielding rollers v^8 impart a certain flexibility to the neck-wiper levers and their rollers.

Operation.—The improved bottle-labeling machine is operated as follows: The hand-lever by which motion is imparted to the driving-shaft is first set in proper position. The foot-treadle is then depressed so that motion is transmitted from the driving-shaft to the cam-shaft. From the cam-shaft the different operative parts are actuated. The attendant places a bottle in position on the bottle-rest. The pickers are then moved in upward direction, turned into vertical position about midway of their ascending motion so that they assume a vertical position and are placed in contact with the paste-supply rollers which are then held in position so as to form contact with the pickers and transfer paste to the same. The pickers are held in vertical position by the stationary guide-plate and returned into horizontal position as soon as they clear the upper end of the same. They are moved in this position un-

der the lowermost labels in the label-receptacles so as to form adhesive contact with the same and pull the same in downward direction away from the lower ends of the fingers of the label-receptacles as soon as the descending motion of the pickers commences. As soon as the labels taken up by the pickers arrive respectively on the body and neck of the bottle, the oscillating presser-arm moves in downward direction through an angle of 90° , so as to hold both labels on the body and neck of the bottle. Simultaneously therewith the pickers are moved upward and the wipers are brought over the ends of the body and neck labels and moved in inward and downward direction so as to apply the gummed ends of the labels in a reliable manner to the body and neck of the bottle. As soon as the labels are applied to the bottle, both sets of wipers are moved in outward direction so as to clear the body and neck of the bottle and permit the removal of the latter from the bottle-rest. A new bottle is then placed on the bottle-rest and the successive motion of the operative parts repeated and the labels that are brought down by the pickers are transferred and applied to the bottle. During the descending motion of the pickers, the paste-supply rollers are moved outwardly so that they take up a new supply of paste by contact with the take-up rollers. During the ascending motion of the pickers the paste-supply rollers are moved inwardly beyond the inner edges of the paste-receptacles, so as to form contact with the pickers, which are turned into vertical position by the rollers and held in vertical position by the guide-plate until they have passed the paste-supply rollers. This arrangement secures the positive turning of the pickers into vertical position, the taking up of the paste by the faces of the pickers, and the returning of the pickers into horizontal position below the label-receptacles so that they can take up the lowermost labels in the same and bring them by their descending motion onto the body and neck of the bottle.

Having thus described my invention, I claim as new and desire to secure by Letters Patent:

1. In a bottle-labeling machine, the combination of a stationary bottle-rest, vertically reciprocating pickers, means for tilting the pickers during their ascending motion, paste-supplying devices, one at each side of the picker-path, label-receptacles above the bottle-rest, an oscillating presser-arm for holding the labels on the bottle, and two pairs of vertically reciprocating and laterally oscillating wipers, one pair for the body-labels and the other for the neck-labels.

2. In a bottle-labeling machine, the combination of a stationary bottle-rest, two sets of vertically reciprocating pickers, one for the body-labels and the other for the neck-

labels, means for tilting the pickers into vertical position during their ascending motion, two sets of paste-supplying devices provided with two sets of paste-supply rollers, one 5 for each set of pickers, two label-receptacles above the bottle-rest, an oscillating presser-arm for holding the body and neck labels transferred by the pickers on the bottle, and two pairs of vertically reciprocating and laterally oscillating wipers for the body and neck labels.

3. In a bottle-labeling machine, the combination of a stationary bottle-rest, two sets of vertically reciprocating and axially turnable pickers respectively for the body and neck labels, two sets of paste-supply rollers for transmitting the paste to the pickers, two label-receptacles above the bottle-rest, two sets of wipers, one for the body-labels 15 and the other for the neck-labels, and means for imparting vertically reciprocating and laterally oscillating motion to said wipers.

4. In a bottle-labeling machine, the combination of a stationary bottle-rest provided 25 with an adjustable stop or gage, two sets of pickers, mechanism for vertically reciprocating the pickers, mechanism for tilting the same during their ascending motion, two sets of paste-supplying devices, one set for each set of pickers, two sets of label-receptacles above the bottle-rest, wipers for the body-labels, wipers for applying the neck-labels, and means for actuating the wipers at 30 the proper time for applying the labels to the body and neck of the bottle.

5. In a bottle-labeling machine, the combination of two sets of paste-supplying devices located at opposite sides of the machine and provided each with paste-supply rollers, 40 two pairs of pickers, one for the body-labels and the other for the neck-labels, mechanism for imparting vertically reciprocating motion to the pickers, mechanism for tilting the pickers when in line with the paste-supply rollers, mechanism for returning the pickers into horizontal position, and two label-receptacles, one for the body-labels and the other for the neck-labels, for delivering the lower-most labels to the pickers when they arrive 45 at the lower ends of the label-receptacles.

6. In a bottle-labeling machine, the combination of a stationary bottle-rest, two sets of pickers, one for the body-labels and the other for the neck-labels, mechanism for vertically reciprocating said pickers, two sets of paste-supply mechanisms, one at each side of the machine and provided each with two pairs of paste-supply rollers, means for tilting the pickers into vertical position so as to 55 take up the paste from the paste-supply rollers, two label-receptacles, one for the body and the other for the neck labels, means for returning the pickers into horizontal position below the label-receptacles, 60 and means for returning the pickers without

being tilted for transferring the labels to the body and neck of the bottle.

7. In a bottle-labeling machine, the combination of two label-receptacles, one for the body and the other for the neck labels, each 70 receptacle consisting of a plurality of pairs of label-supporting fingers, means for adjusting said pairs of fingers for different sizes of labels, a presser device for holding the piles of labels in the label-receptacles, and means for raising the label-receptacles away from the pickers for interrupting the label-feed by the pickers.

8. In a bottle-labeling machine, the combination of a receptacle for the body-labels, 80 a receptacle for the neck-labels, a horizontal presser-bar arranged to bear at its ends on the piles of labels in the respective receptacles, and a vertical center-bar pivoted to said presser-bar and by which the latter is 85 adjusted.

9. In a bottle-labeling machine, the combination of a bottle-rest, a fulcrumed and oscillating presser-arm provided with a pivoted and spring actuated presser-block at 90 its middle portion, and a fixed presser-block at its outer end for holding the body and neck-labels, means for oscillating the presser-arm at the proper time for holding the labels in position on the body and neck of the 95 bottle, and means for cushioning the presser-arm for giving elasticity to the blows.

10. In a bottle-labeling machine, the combination of pivoted levers which carry the wipers for the body-labels, and by means of which said wipers are bodily moved in lateral direction with respect to the bottle, means for actuating said levers, and neck-label wipers supported on and movable with 100 said levers.

11. In a bottle-labeling machine, the combination of a picker-arm supporting cross-head, stationary ways for guiding said cross-head, horizontal picker-arms supported by 110 said crosshead, picker-sleeves placed on said arms, two pairs of pickers supported on said sleeves, means for turning the pickers into vertical position during their ascending motion, means for guiding the pickers while in vertical position, means for returning the pickers into horizontal position, a cam-shaft, a spring-cushioned connecting rod between the cam-shaft and crosshead, and means for imparting reciprocating motion to the spring-cushioned connecting rod from said cam-shaft.

12. In a bottle-labeling machine, the combination of a vertically reciprocating cross-head, guideways for the same, picker-arms supported on said crosshead, picker-sleeves turning on said arms, two sets of pickers supported on the picker-sleeves, cam-levers pivoted at their upper ends to the supporting frame, a spring connecting the lower ends of 125 said cam-levers, a stationary guide-plate in- 130

termidately of said cam-levers, means for turning the pickers into vertical position during their ascending motion, means for returning the pickers into horizontal position 5 when arriving at the upper end of their ascending motion, a yielding spring-cushioned connecting rod pivoted to the crosshead, a cam-shaft, and means for reciprocating the spring-cushioned connecting rod from said 10 cam-shaft.

13. In a bottle-labeling machine, the combination of label-receptacles, horizontal supporting rods for the same, and a crank-mechanism connected with the supporting rods to 15 raise both label receptacles simultaneously and interrupt the label feed.

14. In a bottle-labeling machine, the combination of label-receptacles composed of a plurality of pairs of fingers, horizontal rods for 20 supporting said label-receptacles, a cross-bar connecting said horizontal rods, upright guide-bars for guiding the cross-bar, and a crank mechanism between the cross-bar and frame for raising bodily the label-receptacles for 25 interrupting the label-feed to the pickers.

15. In a bottle-labeling machine, the combination of vertically reciprocating pickers, means for turning the same into vertical position during their ascending motion, paste- 30 receptacles, take-up rollers in said receptacles, oscillating paste-supply rollers, means for guiding the pickers during their ascending motion, and means for moving the paste-supply rollers alternately in contact with the 35 take-up rollers and the ascending pickers.

16. In a bottle-labeling machine, the combination of a pair of vertically reciprocating pickers, means for turning the same into vertical position during their ascending motion, 40 means for guiding the same while ascending, paste-supply receptacles comprising take-up rollers and paste-supply rollers, pivot-links for said paste-supply rollers, oscillating cam-levers pivoted at their upper ends, and a 45 spring connecting the lower ends of said cam-levers, said cam-levers being connected with the shafts of the paste-supply rollers for moving the same alternately in contact with the take-up rollers and the ascending pick- 50 ers.

17. In a bottle-labeling machine, the combination of wipers for the body-label, pivoted levers on which the wipers are supported, means for raising and lowering said levers,

oscillating levers yieldingly connected with 55 said supporting levers, and means for oscillating said last-named levers to produce the lateral movement of the wipers during their reciprocation in vertical direction.

18. In a bottle-labeling machine, the combination of pivoted supporting levers for the body-label wipers, means for raising and lowering said levers, oscillating levers yieldingly connected with said supporting levers and pivoted intermediately of their length, means 60 to actuate one of said oscillating levers, and a connection between the adjacent ends of said levers by which the movement of one is transmitted to the other.

19. In a bottle-labeling machine, the combination, with the bottle-rest, of intermediately pivoted levers, neck-label wipers carried thereby, means for raising and lowering said levers and a guide-plate below the bottle-rest and between and in engagement with 75 the lower free ends of said neck-wiper levers.

20. In a bottle-labeling machine, the neck-label wiper consisting of an elbow-shaped knuckle provided with a guide-roller at the upper end, and slotted wiper-strips having 80 bent-up ends located at the lower end of said knuckle.

21. In a bottle-labeling machine, the combination with pivoted levers which carry the body-label wipers, and means for actuating 85 said levers, of pivoted levers suspended from said first-named levers and movable bodily therewith, and neck-label wipers carried by the last-named levers.

22. In a bottle-labeling machine, the combination of pivoted levers carrying the wipers for the body-labels, means for raising and lowering said levers and at the same time oscillating the same, pins carried by said levers at their upper ends, levers pivoted intermediately of their length and suspended from said pins, said levers carrying neck-label wipers at their upper ends, and a cam-plate by which the lower free ends of the neck-wiper levers are guided.

In testimony that I claim the foregoing as my invention, I have signed my name in presence of two subscribing witnesses.

EDWARD ERMOLD.

Witnesses:

PAUL GOEPEL,
HENRY J. SUHRBIER.
